UNITED STATES PATENT OFFICE.

THOMAS F. KELLY, OF CLINTON, IOWA, ASSIGNOR OF ONE-HALF TO JOSEPH A. KELLY,
OF CLINTON, IOWA.

CONVERTIBLE FURNITURE.

1,318,286.

Specification of Letters Patent.

Patented Oct. 7, 1919.

Application filed February 4, 1919. Serial No. 274,932.

To all whom it may concern:

Be it known that I, THOMAS F. KELLY, a citizen of the United States, residing at Clinton, in the county of Clinton and State 5 of Iowa, have invented a new and useful Improvement in Convertible Furniture, of which the following is a specification.

This invention relates to convertible furniture and is more especially an improvement 10 upon the structure disclosed in Patent Number 1,270,839, issued to W. J. Kelly on July 2nd, 1918.

In a structure of the kind mentioned there is provided a main structure or housing 15 supporting a stationary davenport seat and the back of said seat is movably mounted and is formed of folded sections which, when extended over and beyond the stationary seat, form a bed. For the purpose 20 of facilitating the movement of the bed sections separate springs have been provided within the housing or main structure at the sides thereof but, in order to insure operation of the parts and prevent the parts from 25 being pulled out of line and binding, it has been necessary to exercise considerable care and skill in adjusting the springs at the factory. Very often, however, one of the springs is weaker than the other and after 30 the device has been in use for a time the parts will begin to bind and will not operate properly because of the unequal pulls exerted by the springs at the two sides of the device. This necessitates readjustment 35 by an expert, causes dissatisfaction, and is likely to result in damage to the parts.

It is an object of the present invention to provide a novel form of equalizer and buffer or cushion which is substituted for 40 the separate springs heretofore used and which constantly equalizes the pull exerted at the two sides of the device so that no lateral distortion is possible. A further object is to provide an equalizer which can 45 be regulated readily without requiring the services of a skilled mechanic, and which not only acts to prevent the folded parts from slamming shut but at the same time yieldingly stops the movement of the parts 50 just before being brought to shut position and is put under tension when the parts are completely shut, thereby acting to open the structure automatically for a short distance when it is unlocked.

55 With the foregoing and other objects in

view which will appear as the description proceeds, the invention consists of certain novel details of construction and combinations of parts which will be hereinafter more fully described and pointed out in the 60 claims, it being understood that various changes may be made in the construction and arrangement of the parts without departing from the spirit or sacrificing any of the advantages of the invention as set forth 65 in the appended claims.

In the accompanying drawings the preferred form of the invention has been shown.

In said drawings 70
Figure 1 is a side elevation of a portion of a bed davenport having the present improvements embodied therein, the near side of the main structure or housing being removed and the device being shown extended 75 for use as a bed.

Fig. 2 is a similar view showing the device folded, parts being removed.

Fig. 3 is a rear elevation showing the position of the equalizer when the device is 80 extended for use as a bed.

Fig. 4 is a similar view showing the positions of the parts when the bed is folded.

Fig. 5 is a detail view of a portion of 85 the equalizer.

Fig. 6 is a view showing, in diagram, the action of the equalizer.

Referring to the figures by characters of reference, A designates the main structure or housing of the article of furniture and a 90 seat B is fixedly mounted therein. Said seat has a space between it and the sides of the structure A for the reception of the arms C which are fixedly secured to and extend downwardly from the inner end section D of the bed portion of the device. This bed portion is made up preferably of three sections hingedly connected and adapted to fold together to form the back structure of the device when used as a 100 davenport. As the bed sections, other than section D, constitute in themselves no part of the present invention it has not been deemed necessary to show or describe them all, although in addition to the section D a 105 portion of an adjoining section E has likewise been illustrated. The arms C are pivotally connected to the structure A as shown at c and are adapted to swing between the seat B and the sides of structure 110

A when the back structure is swung forwardly or backwardly relative to the seat B.

Secured to the inner end of the section D at the sides thereof are arms 1 which extend 5 beyond the said end of the section. Brackets 2 are secured to the back of the seat B at the sides thereof and preferably project slightly above the back of the seat as shown. A rod or toggle link 3 is pivotally connected 10 to each of the arms 1 preferably by means of an eye 4 seated loosely within an opening in the arm, and another rod or toggle link 5 is similarly connected to each bracket 2. The rods or links 3 and 5 are thus arranged 15 in pairs and their adjoining ends are provided with eyes 6 which are fitted loosely within eyes 7 formed in the ends of rods 8. These rods, in turn, are connected by a coiled spring 9 and, as shown, one of the 20 rods 8 can be formed of two threaded sections connected by a turnbuckle 10. Thus the tension of the spring can be varied at will.

The action of the equalizer and cushion is 25 as follows: When the bed sections are extended horizontally as shown in Figs. 1 and 3, the spring 9 pulls equally upon all of the rods or links 3 and 5 but the spring is not strong enough to pull the back end of the 30 section D downwardly. After the sections of the bed have been folded together so as to be supported on the section D and directly over the seat section B, the said bed sections are swung backwardly and downwardly to the position shown in Figs. 2 and 35 4. This causes the arms 1 to swing downwardly to position below the brackets 2 and as the distance between the arms 1 and brackets 2 increases during this movement, 40 the links of each pair will swing relative to each other so as to increase the angle between them and pull, through the rods 8, upon the spring 9. The tension of the spring will thus be increased and the parts 45 are so adjusted that the weight of the closing sections will be balanced by the spring just prior to the arrival of the sections to closed position within the back of the structure A. This results in the gradual stopping of the folded sections when moved to closed position and the elimination of slamming. To completely close the structure it becomes necessary to press back on the section D so as to further increase the distance 50 between the arms 1 and brackets 2 and correspondingly increase the tension of the spring. Any suitable lock can be provided for holding the back in closed position, as shown generally at 11. When the section D 55 is unlocked the spring 9 will automatically shift it to balanced position where it can be grasped readily and opened out to form an extension bed as before described.

Importance is attached to the fact that 60 65 the single spring equalizes the pull upon all

the rods and the sections are always properly centered. The tension of the spring can be varied readily by means of the turnbuckle and the construction is simplified and the entire structure made more efficient by 70 the use of the improvement.

What is claimed is:—

1. The combination with a seat, of a back section hingedly connected thereto and adapted to swing to position thereover, and 75 equalizing means for facilitating the movement of said section from either extreme position, for cushioning said section when approaching one extreme position, and for counterbalancing said section before reaching 80 its other extreme position, said means including separate toggles connecting the rear portions of said seat and section, and a spring connecting the toggles and fastening means for holding the back section in 85 the last named extreme position when thrust past its counterbalanced position, thereby to hold the spring under increased tension.

2. The combination with a seat, of a back section hingedly connected to the seat and 90 movable to position over the seat and into upstanding position at the back of the seat, said section, when in upstanding position, having its lower portion extended below the seat, and equalizing means for facilitating 95 the movement of said section from either extreme position, for cushioning said section when approaching one extreme position, and for counterbalancing said section before reaching 100 its other extreme position, said means including toggles connecting the rear portion of the seat to the back or bottom end of the back section, and a spring connection between the toggles, said back section being movable past its counterbalanced position to place the spring under 105 increased tension.

3. The combination with a seat and a movable back section, of equalizing means for facilitating the movement of the back 110 section from either of two extreme positions, for cushioning said back section when approaching one extreme position, and for counterbalancing said section before reaching 115 its other extreme position, said means including a toggle adjacent each side of the back of the seat, one end of each toggle being connected to the seat, and a spring connected to the intermediate joints of the toggles, said back section being connected 120 to the other ends of the toggles and mounted to swing upwardly and backwardly relative to the seat to shift the toggles and place the spring under tension to counterbalance the back section and thence past counterbalanced position to place the spring under increased tension.

4. The combination with a seat, of a back section movable to position over the seat to constitute a bed section and to upstand- 125 130

ing position above the back of the seat to constitute a seat back, said section, when in upstanding position having its lower end projecting below the top of the seat, and 5 means extending transversely of the seat adjacent the back thereof, for yieldingly connecting the seat and the back section, said means including toggles connected to the top portion of the back of the seat at 10 the sides thereof and to said lower end of the upstanding back section, and an adjustable spring connection between the toggles and parallel with the back of the seat

and with the inner end of the back section, said toggles and spring being adapted to 15 swing about their connections with the seat during the upward and downward movement of the back section relative to the seat, thereby to cushion the back section when brought to one extreme position and to 20 counterbalance said back section prior to reaching its other extreme position.

In testimony that I claim the foregoing as my own, I have hereto affixed my signature.

THOMAS F. KELLY.
